GROUND-CONTACTING SURFACE FOR
SHOE SOLES

Isidor Hoffenberg, Milford, Conn., assignor to A. Werman & Sons, Inc., Brooklyn, N. Y., a corporation of New York

Application January 10, 1951, Serial No. 205,287

7 Claims. (Cl. 36—59)

1

This invention relates to shoe soles and more particularly is concerned with the ground-contacting surfaces for the outsoles of shoes which have improved traction characteristics and have longer life in wear without impairing the flexibility of the sole and without adding greatly to the weight and the bulk of said outsole.

In the production of rubber and composition shoe soles, i. e. including the forepart, shank and heel portions, various forms of ground-contacting projections extending outwardly from the general plane of the sole have been adopted to increase the traction characteristics of said soles. However, a shoe sole is subject to considerable flexing so that the sole must have great flexibility along its longitudinal axis, that is, the axis running generally from the forepart of the sole, through the shank, to the heel. There must be a particularly great amount of flexibility on the longitudinal axis in the area between the shank and the toe beneath the ball of the foot. When the projections which are provided on soles extend parallel to the longitudinal axis or diagonally thereto and add thickness to the sole along that axis in the area beneath the ball of the foot, the rigidity of the sole is increased and the flexibility thereof is impaired.

To obviate the impairment of the flexibility of the sole along its longitudinal axis, projections have been provided which run transverse to the longitudinal axis. In this manner, the flexibility of the sole along its longitudinal axis is not materially reduced for there is no continuous portion of added thickness parallel to said axis. The transverse ribs or projections also provide quite adequate traction against slipping along the longitudinal axis, but, they provide very little traction against transverse slippage. Frequently such transverse ribs are provided with auxiliary diagonal or longitudinal ribs in order to increase the transverse traction. However, the addition of such ribs either parallel or diagonal reduce the flexibility of the sole.

An important object of the present invention is to provide an outsole having improved longitudinal and transverse traction characteristics without any material reduction of the flexibility of the sole.

Another object of the invention is to provide an outsole which will have an increased wearing life without greatly increasing the weight or bulk of the sole.

A still further object is to provide an outsole which retains improved traction characteristics throughout its useful life.

The invention includes a ground-contacting

surface for the soles of shoes having parallel ribs projecting from the plane of a shoe sole, the axes of said ribs being disposed at substantially right angles to an axis running the length of the sole from the heel to the toe. Each of the ribs is provided with a plurality of spaced projections formed on its surface, the projections extending outwardly from the axis of the rib and substantially transverse thereto. Similar parallel projection-bearing ribs are provided on the raised heel which is affixed to the sole. The ribs on the heel, however, do not extend above the plane of the raised heel but only outward to co-planar relation with the heel from a centrally disposed area recessed below the plane of said heel.

For a more complete description of the invention, reference is made to the drawings wherein:

Fig. 1 is a plan view of a shoe sole, including a heel, embodying the invention;

Fig. 2 is a side view of the sole;

Fig. 3 is an enlarged vertical section of a portion of the sole, taken parallel to the longitudinal axis of the sole;

Fig. 4 is an enlarged plan view of a portion of the sole before it has been subjected to wear; and

Fig. 5 is an enlarged plan view of a portion of the sole after it has been subjected to wear.

The sole 10, which is the ground-contacting or outsole for attachment to a shoe, includes a forepart 11, a shank 12 and heel 13. Suitably flexible material such as rubber or composition plastic material may be used to form the sole 10 with the desired traction characteristics.

Referring first to the configuration of that portion of sole from the shank 12 to the toe 15, the sole is formed with a substantially planar surface 16 which extends around the margin 13 of forepart 11 and across the shank 12. The sole 10 is provided with a centrally disposed portion 17 projecting above the plane of the sole surface 16. The forepart 11 of the sole 10 is subjected to great wear in the area indicated at 17 and therefore the raised portion by adding increased thickness to the sole increases the wearing life of the sole.

The raised portion 17 includes a raised pad 18 adjacent to the toe 15. The pad 18 may be solid and provided with suitable traction improving means such as the cross hatching shown.

Extending from the rear of the toe pad 18 to the beginning of the shank 12, the raised portion 17 is formed of a series of parallel, spaced ribs 20 projecting from the plane of the surface 16. The axes 21, indicated by dotted lines in Fig. 1, of the ribs, are disposed across the sole so that they run transversely to the longitudinal axis 22, i. e., the axis extending from the rear 23 of the heel 13 to

55

the toe 15, indicated by dot-dash lines in Fig. 1.

The parallel ribs 20 may be of any suitable cross-sectional shape, and for purposes of illustration are shown as being generally frusto-pyramidal in form, the base or broader portion of the ribs being integrally joined to the surface 16 of the sole 10. The ribs 20 are provided with projections 28 extending upwardly and outwardly from the axes 21 of the ribs. The projections 28 on each rib are spaced apart along the rib and are disposed substantially transverse to the axis 21. In the embodiment shown, the projections 28 taper, toward the planar surface 16, into the sides 31 of ribs 20 so that there is no addition to the thickness of sole 10 between the ribs which would cause a loss of flexibility in the critical area along the longitudinal axis 22 between the toe pad 18 and the portion 25.

In use the projections 28 serve the important function of providing traction against side slipping, i. e. slipping at right angles to the longitudinal axis 22 of the sole. The improved traction is achieved by interrupting the parallel lines 30 which define the edges of the ribs 20 at the truncated tops 32. The interruptions provided by the projections 28 increase the frictional drag when slipping of the sole occurs along the axes 21 of the ribs 20.

It will be noted that the projections 28 with their extensions from the sides 31, as well as from the truncated top 32 of the ribs 20, provide good traction even after wear has abraded the ribs to a level such as that indicated by the dot-dash line 33 in Fig. 3. Fig. 5 shows an enlarged plan view of the shoe sole 10 after it has been subjected to wear, down to the level indicated by the line 33 in Fig. 3. The projections 28 at the level indicated continue to act as effective interruptions of the straight lines 34 formed by the sides 31 and the worn down tops of the ribs.

The toe pads 18 which are out of the area in which the greatest flexibility is required are, as noted, substantially solid raised platforms to provide a particularly reinforced wearing area at the front of the sole because of the greater wear which that area is subjected to due to toe scuffing.

The heel 13 may be formed of material similar to that of the shank and forepart of the sole and may be a separate piece attached to the general plane 16 of the sole, as shown in Fig. 2 or may be formed as an integral portion of the sole 10. In either case, however, the ground-contacting surface 35 of the heel 13 is a pad or platform extending beyond the general plane 16 of the sole 10. The marginal areas 36, shown in Fig. 1, are substantially co-planar and lie in the plane of the surface 35. A centrally disposed recess 37 is formed in the heel. The floor 38 of the recess is a plane substantially parallel to the ground-contacting surface 35 of the heel. Ribs 40 which are parallel to each other and spaced apart project from the floor 38. The axes 41, indicated by the dotted lines in Fig. 1, of the ribs 40, are substantially at right angles to the longitudinal axis 22 of the sole 10. It will be noted that the ribs 40 of the sole and the ribs 20 of the heel are parallel to each other.

Projections 42 are formed on each of the ribs 40 and extend outwardly from each of the axes 41. The ribs 40 and their projections 42 may be of the same general configuration as the ribs 20 and projections 28, or they may be of any other suitable shape. For purposes of illustrating another form which the ribs and projections may take, the ribs 40 are shown as having arcuate

cross-sections (see Fig. 2). The projections 42 on the ribs 40 may be spiral in form running diagonally to the axes 41. The portions of the ribs 40 and their projections 42 remote from the floor 38 of the recess lie substantially in the plane 35 of the heel 13.

The projections 42 which are arranged substantially transverse to the axes 41 of the ribs 40 serve as a means for improving the traction characteristics of the heel portion of the sole to reduce the possibility of slipping sidewise, i. e. parallel to the axes 41.

The ribs 40 arranged transversely to the longitudinal axis 22 serve in the same manner as the ribs 20 to prevent slipping or loss of traction parallel to the axis 22.

At the portion of the forepart 11 adjacent the shank 12, an area 25 may be provided on which a suitable legend such as a trade-mark or other device may be formed in raised characters or otherwise. The area 25 may be a solid raised pad as shown and will assist in increasing the wearing life of the sole.

The end 27 of the area 25 may have the curved form shown or have any suitable configuration for decorative purposes.

The area in which the greatest flexibility is needed along the longitudinal axis 22 is between the pad 18 and the portion 25. Consequently no continuous thickened portion running parallel to the said longitudinal axis is provided which would reduce flexibility in that area.

In use the sole 10 will flex so that the toe pad 18, the portions of the projections 28 across the truncated tops 32 of the ribs 20, and the surface 35 of the heel 13 will be in contact with the ground.

The wearer of shoes having outsoles embodying my invention is protected against lengthwise slippage by the ribs 20 and 40 and against side slippage by the projections 28 and 42. The sole has a longer wearing life due to the increased thickness provided by the toe pad 18, the ribs 20, and the portion 25, but there is little or no diminution of the flexibility of the sole for there is no continuous thickening of the sole parallel to the longitudinal axis 22, particularly in the area between the toe pad 18 and the portion 25, which is the area in which greatest flexibility is needed. Furthermore, the increased wearing life of the sole is achieved without materially increasing the weight or bulk of the sole, as would result if the entire sole were thickened.

The margins 43 of the forepart 11 are left free of ribs or other projections so that the outsole may be readily stitched or otherwise attached to a shoe and also because it has been found that by the provision of the raised ribs in the central portion which is the area of greatest wear, there is substantially no wear adjacent the margins of the sole. Furthermore, if the ribs were extended to the edges of the sole, the weight and bulk of the sole would be increased so that it would be quite clumsy.

In accordance with the provisions of the patent statutes, I have described herein the principles of this invention, together with the best mode of carrying out those principles. However, it will be understood that the structure disclosed is only illustrative and the invention may be carried out by other means. Also, while it is designed to use the various features and elements in the combination and relations described, some of these may be altered and modified in ways other than those

suggested without departing from the spirit and scope of the invention.

I claim:

1. A ground contacting surface for the sole of a shoe, having a forepart, a shank, and a heel portion, comprising, a planar outer surface of the sole, parallel ribs projecting from the plane of said surface, the axis of said ribs being disposed at substantially right angles to an axis running from the heel through the shank and the forepart of the sole, each of said ribs having a plurality of projections integrally formed thereon extending outwardly from the axis of the rib.

2. In a shoe sole having a forepart, a shank and a heel portion, a ground contacting surface projecting from the plane surface of the forepart, comprising, a plurality of parallel spaced ribs projecting from the plane surface of the forepart, the axes of said ribs being disposed transversely to an axis running longitudinally along the sole from the heel to the forepart and a plurality of projections extending outwardly from the axis of each of said ribs and integrally formed thereon, the projections being substantially transverse to the axes of the ribs.

3. A ground contacting surface for the sole and heel in a shoe having a planar forepart and shank, and a planar heel portion raised above the plane of the forepart and shank, comprising, a plurality of spaced parallel ribs, projecting from the plane of the forepart, having their axes disposed substantially at right angles to an axis of the sole which runs from the heel to the forepart, a plurality of projections extending outwardly from the axis of each of said ribs, a centrally disposed recess formed in the plane of the heel, having parallel ribs formed on the floor of said recess and extending outwardly to the plane of said heel, the axes of the ribs formed in the heel recess being substantially transverse to the axis of the sole, and a plurality of projections extending outwardly from the axes of the ribs in the heel recess.

4. The ribs of claim 1 having generally frusto-pyramidal cross sections with the base of each rib being integral with the planar surface of the forepart of the sole.

5. In a shoe sole having a forepart, a shank and a heel portion, an outer surface provided on the heel portion, comprising, a planar surface extending about the marginal edges of the heel portion and adapted to contact the ground, said heel portion being formed with a centrally disposed recess having a recessed floor parallel to the ground contacting surface of said heel, a plurality of parallel spaced ribs projecting from the floor of the recessed portion, the axes of said ribs being transversely disposed to an axis of the sole running from the heel to the forepart of the sole, projections formed on said ribs and extending outwardly from the axis of each rib so that the portions of the projections on the ribs which are most remote from the recessed floor are substantially co-planar with the planar ground contacting surface of the heel.

6. A ground contacting surface for a shoe sole and heel in a shoe having a planar forepart and

shank and a planar heel portion raised above the plane of the forepart and shank, comprising, in combination a plurality of spaced parallel ribs formed to project from the plane of the central part of the forepart, said ribs having their axes disposed substantially at right angles to an axis of the sole which runs from the heel to the forepart, a plurality of projections formed on said parallel ribs and extending outwardly from the axis of each of said ribs, a centrally disposed recess formed in the planar surface of the heel, said recess having a floor parallel to said planar surface of the heel, a plurality of parallel spaced ribs formed to project from the floor of the recessed portion, the axes of said ribs being disposed at right angles to the axis of the sole, projections formed on the ribs in the recessed heel portion and extending outwardly from the axis of each of said ribs, the ribs in the heel portion extending outwardly so that their outward extension lies substantially in the plane of the heel.

7. A ground contacting surface for a shoe sole and heel in a shoe having a planar forepart and shank and a planar heel portion raised above the plane of the forepart and shank, comprising, in combination, a plurality of spaced parallel ribs formed to project from the plane of the central part of the forepart, said ribs having their axes disposed substantially at right angles to an axis of the sole which runs from the heel to the forepart, a plurality of projections formed on said parallel ribs and extending outwardly from the axis of each of said ribs, a toe pad projecting from the plane of the forepart adjacent the toe of the sole, a raised pad formed on the planar surface of the forepart in an area adjacent the shank, a centrally disposed recess formed in the planar surface of the heel, said recess having a floor parallel to said planar surface of the heel, a plurality of parallel spaced ribs formed to project from the floor of the recessed portion, the axes of said ribs being disposed at right angles to the axis of the sole, projections formed on the ribs in the recessed heel portion and extending outwardly from the axis of each of said ribs, the ribs in the heel portion extending outwardly so that their outward extensions lie substantially in the plane of the heel.
